DESIGN FOR A PARING KNIFE

Charles F. Senkewitz, Dearborn, Mich.

Application July 12, 1938, Serial No. 78,422

Term of patent 7 years

To all whom it may concern:

Be it known that I, Charles F. Senkewitz, a citizen of the United States, residing at Dearborn, in the county of Wayne and State of Michigan, have invented a new, original, and ornamental Design for a Paring Knife, of which the following is a specification, reference being had to the accompanying drawing, forming a part thereof.

Fig. 1 is an end elevational view of a paring knife showing my new design.

Fig. 2 is a bottom plan view of a knife showing my new design.

Fig. 3 is a side elevational view of a knife showing my new design.

Fig. 4 is a side elevational view of the knife from the other side.

What I claim is:

The ornamental design for a paring knife, as shown.

CHARLES F. SENKEWITZ.
